[57] CLAIM

The ornamental design for atomizer nozzle, as shown
and described.

DESCRIPTION

FIG. 1 is a top plan view of an atomizer nozzle showing
my new design;

FIG. 2 is a left side elevational view thereof, which is a
mirror image of the right side;

FIG. 3 is a front elevational view thereof which is a
mirror image of the rear; and

FIG. 4 is a bottom plan view thereof.
